UNITED STATES PATENT OFFICE.

GUSTAV ERNST STRANDT, OF MILWAUKEE, WISCONSIN.

SASH-ADJUSTING MECHANISM.

Application filed December 10, 1924. Serial No. 754,923.

This invention relates to improvements in sash adjusting mechanism.

It is the primary object of this invention to produce a novel and simple sash adjusting mechanism so organized that either sash of a double hung window may be adjusted upwardly or downwardly by a single manually operable device such as a crank or the like, the mechanism being so organized as to lock the sash positively against movement when the crank is not operative for adjusting purposes.

The employment of a single hand lever for any desired manipulation or for the locking of the sash results in the production of a neater and more compact device than has heretofore been employed for these purposes to my knowledge. It is an object of the present invention to produce a device for these purposes in which the operating parts can quite largely be concealed and merely the manually operable lever or crank will be visible.

As has already been stated, it is one of the objects of this invention to provide for locking the sash in any desired positions of adjustment. In order to accomplish this result more effectively than would otherwise be the case, it is one of the purposes of the invention to conceal all of the sash actuating connections within the window frame, there being no cords or other sash supporting mechanism exposed at any time, whether the sash be open or closed.

Further objects of the invention are to provide a novel and simplified and very compact device for the purposes aforesaid; to eliminate sash weights, sash locks, sash lifts or handles and to economize in the space required for window frames; and to prevent the possibility of accidental sash movement by using a single manually operable part for locking and for sash adjusting purposes, and by providing means ensuring that each sash will be kept locked until it is practically completely clutched to said part, and will be again locked before being fully released from said part.

In the drawings:

Figure 1 is a front elevation of a double hung sash window provided with sash adjusting means embodying this invention, portions of the window frame being broken away to expose the actuating connections.

Figure 2 is a side elevation of the device shown in Figure 1.

Figure 3 is a detail taken on line 3—3 of Figure 1.

Figure 4 is a section taken on line 4—4 of Figure 1 through the control mechanism of a sash actuating device embodying this invention.

Figure 5 is a detail view in section taken on the line indicated at 5—5 in Figure 4.

Figure 6 is a detail view in transverse section through a locking collar which normally holds the sash against movement.

Figure 7 is a detail view in plan of a modified spool construction for use in the sash adjuster shown in Figure 4.

Figure 8 is a detail view in section on the line indicated at 8—8 in Figure 7.

Like parts are identified by the same reference characters throughout the several views.

10 represents a window frame in which upper sash 11 and lower sash 12 are vertically movable as in the ordinary double hung window.

Adjacent the middle of the frame upon each side thereof are horizontally and vertically offset fittings 14 which may be identical in construction, and which may each include a pair of co-axial pulleys 15 and a second pair of co-axial pulleys 16. The side margins of the sash are preferably substantially tangential to these pulleys, and the fittings 14 are so located that one of them will be approximately at the bottom of the upper sash and the other will be approximately at the top of the lower sash.

At the bottom of the frame, upon each side thereof, is a bracket 17 from which four aligned pulleys 18 are supported, as indicated. It will be understood that with regard to each of the features above mentioned, the two sides of the window frame will be identical with the single side thereof which is shown in Figures 1 and 2. In fact, it is only desirable to duplicate the mechanism thus far described upon the opposite side of the window frame for the purpose of balancing pressures acting upon the sash, whereby to prevent the sash from sticking.

Disposed centrally beneath the frame is a control mechanism designated in its entirety by reference character 20. This mechanism comprises an important part of the present invention and will hereinafter be more fully

- described. For the present it suffices to say that such mechanism includes a housing 21 from which a crank projects at the front and from which issue at each side of the 5 machine flexible sash actuating connections which, for the purpose of illustrating typical connections in the present application, are represented to comprise metal tapes or ribbons 22, 23, 24, and 25.
- 10 Each of these metallic ribbons or tapes passes about one of the pulleys or guides 18 at the bottom of the window frame and thence passes upwardly toward the fittings 14. The tapes are guided over the pulleys 15 of such fittings in various ways which will now be described. Tape 25 passes around the outside of one of the pulleys 15 of the lower fitting 14 and thence downwardly toward the bottom of the bottom sash to which 20 it is secured. The sash may conveniently be cut away, as indicated at 27, and a wedge-shaped block 28 may be screwed to the sash to hold the end of the tape or ribbon thereto. Preferably, the sash is grooved throughout its entire length to receive the tape or ribbon 25, whereby to conceal and enclose the ribbon. It will be obvious that when the ribbon 25 is drawn into the housing 21 of the control mechanism the result will be 30 that the tape in passing over pulleys 18 and 15 will exert a lift upon the lower sash 12 tending to raise that sash.
- 35 The tape or ribbon 24 passes about the second of pulleys 18 and fitting 17 and thence passes through from the outside of pulley 16 to the inside of pulley 15 on the lower of the two fittings 14. It is thereupon secured to the upper end of the lower sash 12 in a manner similar to that already de- 40 scribed with reference to the lower end of said sash. It follows that tape 24 must be paid out to permit the sash to rise under the pull of tape 25. When it is desired to lower the sash, however, such an operation 45 may be accomplished by drawing ribbon 24 into housing 21 and paying out ribbon 25 at a corresponding rate.
- 50 In a similar manner the upper sash is actuated by ribbons 22 and 23. Ribbon 23 issues from the lower part of housing 21, passes about one of the rollers or pulleys 18, and passes about pulley 15 to engagement with the lower portion of sash 11 to which it is held by one of the wedge-shaped blocks 55 28 screwed through the ribbon to the sash. Ribbon 22 issues from the upper part of case 21, passes about the last of rollers 18, and thence passes upwardly from the outside of roller 16 to the inside of roller 15 in the uppermost of the two fittings 14. Thence tape 22 passes to the top of sash 11 where it is secured by one of the blocks 28. Obviously, the sash 11 will be caused to move by drawing one of ribbons 22 or 23 60 into case 21 and simultaneously paying out 65 the other of such ribbons at a corresponding rate. In discussing the several ribbons 22, 23, 24, and 25, it will of course be understood that the ribbons are only illustrated as representative of any suitable flexible motion transmitting connections. Similarly, the pulleys are to be understood to be merely representative of any of the well known means whereby a change in direction may be given to the ribbons or similar flexible 70 connections. Suitable slots 29 in the upper sash receive and house the flexible connections just as these connections are preferably housed in the lower sash.
- 75 Casing 21 includes front and rear plates 30 and 31, respectively, and a substantially tubular wall 32 which may conveniently be screwed to annular flanges 33 carried by the front and rear plates.
- 80 A shaft 35 is journaled in the front and rear walls 30 and 31 of housing 21 and projects from the housing at the front where it is provided with a hand crank 36 rigidly connected thereto. The hand crank and shaft may be moved forwardly and rearwardly as well as rotated.
- 85 The front and rear plates of housing 21 are each provided with an inner annular flange 37 at the inside of which is a bearing sleeve 38 and at the outside of which is a 90 positioning sleeve 39, these sleeves being secured to the annular flange 37 by suitable screws 40. The central bore in bearing sleeve 38 may be fitted closely about shaft 35 at the outer end of each such sleeve, but the inner end of each sleeve is counter-bored at 42 to afford clearance for sleeves 43 which are connected with shaft 35 and may be formed integrally with a clutch device 45 mounted upon said shaft. The clutch device 105 may conveniently take the form of a spider having arms 46 from which the clutch pins 47 project forwardly and clutch pins 48 project rearwardly. A key or a cross pin 49 may be utilized to secure the entire clutch 110 device to the shaft, the arrangement being such that the clutch device will rotate and move axially with the shaft by reason of such connection.
- 115 Each of the bearing members 38 is slotted in the manner indicated at 50 to receive studs 51 which are formed integrally with the spring-pressed lock clutch collar 52. A compression spring 53 seated behind each such collar and confined between the collar and the end of flange 37 serves to press each such collar toward the center of the device. The collar is provided at 54 with clutch teeth which are thereby forced normally into engagement with corresponding teeth 55 on 120 the spools 56.
- 125 Each bearing sleeve 38 is provided with a radial head or flange 57 at its outer end. Spools 56 are journaled upon the sleeves 38 and are confined against axial movement by 130

contact with flanges 57 on the inside and the ends of positioning sleeves 39 on their outside portions. Each spool includes an inner end flange 60, an intermediate flange 61 and an outer end flange 62. Between these flanges the several tapes or ribbons heretofore discussed are wound and unwound during the rotation of spools 56. The normal engagement of teeth 54 and 55 will normally prevent the operation of either spool, due to the fact that the collars 52 are secured against rotation by the engagement of their pin portions 51 in slots 50 of the relatively stationary bearing sleeve members 38. Thus, in the normal position of the parts, it will be impossible for either of the window sash to move either upwardly or downwardly.

If desired, the depth of the housing 21 may be shortened by a slight modification in the construction of the spools or drums 56 upon which the tapes are wound.

In the construction already described the tapes are wound side by side within a given spool, the modification contemplates the winding of each pair of tapes simultaneously upon a given spool so that the width of the tapes may be increased to some extent and still the combined length of the spools 30 may be materially reduced. Figures 7 and 8 show how this may be done. The modified spool 56' has flanges 60, 61, and 62 corresponding to those already described. The separation of these flanges has been reduced, 35 however, and the tapes 22 and 23 have been so increased in width that each of the tapes 22 substantially fills the space between 61 and 62 and each of the tapes 23 substantially fills the space between 60 and 61. Figure 8 40 shows how the tape 23, which is led to the bottom of the spool from the left hand side thereof, is secured thereto at 63 while the tape 23 which arrives from the right of the spool and is led to the top thereof is secured 45 to the spool at 64. The coils of the two tapes are alternated by simultaneous winding upon the spool as is clearly indicated.

Each of the spools 56 is provided at 65 with recesses or openings to receive pins 47 or 48 of the manually operable clutch member 45. It is obviously necessary for the engagement of the pins carried by such clutch member with either of spools 56 that the clutch member and the shaft 35 upon which it is mounted must move axially to effect the engagement. The shaft and clutch member are illustrated in their central or neutral position.

When it is desired either to raise or lower either of the sash 11 or 12 of the window, the operator will grasp the grip portion 66 of the hand lever or crank 36 and will first push the hand lever axially to engage the clutch element 46 with one of the spools 56. According as the rearmost or the forward

spool 56 is engaged, the upper or lower sash will be actuated when the crank 36 is rotated. In order, however, to permit the rotation of spools 56 it is necessary to disengage the spring-pressed lock clutch collar 70 52. The sleeves 43 carried by clutch member 45 effect such disengagement through contact with pins 51, thereby, as the clutch member 45 is forced forwardly or rearwardly, the forward or rearward collar 52 75 is forced in a like direction against the pressure of its respective spring 53. Thus, the movement of the clutch is opposed by one of the springs 53 and, when the operator releases handle 36 the compression of spring 80 53 will preferably be adequate to restore the parts to their neutral position. It is particularly to be noted that the length of slots 50 limits the extent to which the springs can force clutch member 45, and thereby prevents any possibility that such member might be pressed past the desired neutral point.

The length of pins 48 is preferably such with regard to the distance between the neutral clutch member 45 and the spools 56 90 upon either hand, and the length of the lock releasing sleeves 43 is such that the pins 47 or 48 will engage apertures 65 before the teeth 54 locking the collar 52 are released. 95 This ensures that the sash will at all times be under the full control of the operator or of the automatic locking mechanism above described.

It will be obvious from the foregoing that when shaft 35 has been pushed to its limit of movement in either axial direction the locking mechanism which normally secures one of the spools 56 against rotation will be released from such spools and, prior to such release, the clutch member 45 will be engaged with that same spool. The operator may now rotate crank 36 for the purpose of rotating the spool 56 with which the clutch member 45 is engaged, and thereupon one of the flexible connectors attached to a given sash of the window will be paid out and another of such connectors will be wound up onto its spool. This last mentioned operation results from the fact that with reference to each of the spools 56 one ribbon leads to its top and another to its bottom portion from each side of the window frame. Thus, for a given direction of rotation of the spool the ribbon leading to the top thereof may be wound upon the spool while the ribbon leading from the bottom thereof will be unwound therefrom. To each of spools 56 are led all of the connectors which are attached to a given sash.

From the foregoing it will appear that the device herein disclosed is adapted to retain each of two window sash normally locked, the actuating handle for the sash being normally disengaged from the sash

and freely rotatable in either direction without affecting the position of either sash. Furthermore, the handle may readily be adjusted axially for engagement with a spool 5 connected with a given sash which it is desired to operate. The act of connecting the handle with such spool automatically unlocks the spool for rotation, and the unlocking operation is performed subsequent to the 10 engagement of the handle with the spool which it is desired to operate. If the spool is now rotated in one direction the sash will be raised, and if the spool is operated in a reverse direction the sash will be lowered. 15 When the operator releases the handle, all the parts are restored to their normal neutral position and the spool is locked against further rotation before the handle is fully released therefrom.

20 I claim:

1. In a device of the character described, the combination with a member supported for rotation, of a handle rotatably and axially movable and provided with a clutch 25 adapted to engage and disengage said member upon the axial movement of said handle, a locking device including a clutch restrained against rotation and axially adjustable to and from engagement with said member, and actuating means between said handle and said locking device for disengaging the clutch of said locking device from said member upon the engagement of the clutch of said handle therewith.

30 2. In a device of the character described, the combination with a member supported for rotation, of a handle rotatably and axially movable and provided with a clutch 35 adapted to engage and disengage said member upon the axial movement of said handle, a locking device including a clutch restrained against rotation and axially adjustable to and from engagement with said member, actuating means between said handle 40 and said locking device for disengaging the clutch of said locking device from said member upon the engagement of the clutch of said handle therewith, and a spring pressing the clutch of said locking device toward a 45 position for engagement with said member, whereby normally to maintain said member locked against rotation.

50 3. In a device of the character described, the combination with a member supported for rotation, of a handle rotatably and axially movable and provided with a clutch 55 adapted to engage and disengage said member upon the axial movement of said handle, a locking device including a clutch restrained 60 against rotation and axially adjustable to and from engagement with said member, actuating means between said handle and said locking device for disengaging the clutch of 65 said locking device from said member upon the engagement of the clutch of said handle

therewith, and a spring pressing the clutch of said locking device toward a position for engagement with said member, whereby normally to maintain said member locked against rotation, said actuating connections being adapted to transmit the pressure of said spring to said handle, whereby to maintain said handle normally disengaged from said member.

4. In a device of the character described, 75 the combination with a plurality of rotary members provided with connections adapted to transmit movement of a handle supported for axial and rotative movement and provided with a clutch intermediate said members and selectively engageable with either thereof for the rotation of the member so engaged, locking devices normally engaging each such member independently, and motion transmitting connections operable upon the axial movement of said clutch and adapted to release the locking device acting upon a member so engaged.

5. The combination of a plurality of drums, a manually operable shaft co-axial with said drums and mounted for axial adjustment therethrough and for rotation, a clutch mounted upon said shaft intermediate said drum and selectively engageable with either drum, whereby to transmit there-to the rotative movement of said shaft, locking clutches supported for movement to and from engagement with said drums, motion-transmitting connections adapted to be acted upon by said first mentioned clutch to disengage one of said locking clutches upon the engagement of said first mentioned clutch with a drum, whereby to permit the rotation of a drum so engaged, and a spring operating upon each locking clutch and pressing it toward a position for engagement with the drum, said connections being adapted to transmit the pressure of said spring to said first mentioned clutch whereby to maintain it normally in a neutral position intermediate said drums, together with means for limiting the operation of said spring-pressed connections upon said first mentioned clutch, said means being adapted to free said clutch of pressure from either of said springs when said first mentioned clutch is in its neutral position.

6. In a device of the character described, the combination with a pair of drums supported for rotation of a manually operable shaft co-axial with said drums and supported for axial and rotative movement, a clutch element carried by said shaft and engageable selectively with either of said drums, other clutch elements selectively engageable individually with particular drums upon axial movement with respect to such drums, stationary sleeves providing bearings for the axial movement of said other clutch elements and provided with slots, pins connected 120 to 125 130

with said other clutch elements and projecting into the slots of their respective sleeves whereby to key said elements against rotation, the length of the slots being adapted to 5 restrict the axial movement of said last mentioned elements, springs acting upon said last mentioned elements and pressing them respectively toward a position for engagement with their respective drums, and a 10 sleeve connected with said first mentioned element and adapted, upon the movement thereof, to contact pins connected with one or the other of said other clutch elements, whereby to force it out of engagement with 15 its respective drum against the compression of its respective spring.

7. The combination with a pair of spools,

of a handle provided with disengageable connections with said spools for the simultaneous rotation thereof in either direction, 20 and a lock normally operative to restrain said spools against rotation whereby to secure said sash against movement.

8. The combination with a pair of drums each provided with a plurality of spool portions, of a handle rotatably and axially movable, a clutch connected with said handle and adapted upon the axial movement thereof to engage selectively with either of said drums, and locking clutches independently 30 pressed toward engagement with individual drums and adapted normally to maintain said drums non-rotatable.

GUSTAV ERNST STRANDT.
